UNITED STATES PATENT OFFICE

132,724

DESIGN FOR A PHONOGRAPH CABINET

Henry T. Roberts, Chicago, Ill., assignor to Automatic Instrument Company, Grand Rapids, Mich., a corporation of Michigan

Application April 5, 1941, Serial No. 100,171

Term of patent 7 years

To all whom it may concern:

Be it known that I, Henry T. Roberts, a citizen of the United States and resident of Chicago, in the county of Cook and State of Illinois, have invented a new, original, and ornamental Design for a Phonograph Cabinet, of which the following is a specification, reference being had to the accompanying drawing, forming part thereof.

The figure is a front perspective view of a phonograph cabinet, showing my new design.

The right-hand side of the cabinet, not shown in the drawing, is identical to the left-hand side, which is shown.

The rear of the cabinet is plain.

The junction between the dome top and the plane of the horizontal flat top of the cabinet is substantially circular.

The characteristic features of my design reside in the portions shown in solid black lines in the drawing.

I claim:

The ornamental design for a phonograph cabinet, as shown and described.

HENRY T. ROBERTS.
